WILLIAM J. DUNLAP, OF LONG BEACH, CALIFORNIA

GAS ANCHOR AND SAND SEPARATOR

Application filed March 13, 1929. Serial No. 346,591.

This invention relates to a gas anchor and sand separator which has been primarily designed to be used in oil wells beneath the pump.

5 An object of the invention is to provide an improved device adapted to be associated with a deep well pump and which serves to effectively separate the gas from the oil so that the gas will not enter the working barrel of 10 the pump, interfering with the proper closing of the pump valves.

Another object of the invention is to provide a device which is so constructed that sand in the oil is effectively caused to be separated 15 therefrom before the oil or other liquid enters the pump so that the sand will not cut the pump valves and their seats.

A further object of the invention is to provide a gas anchor and sand separator which 20 is of simple and durable construction and which may be easily and quickly applied to any deep well pump of conventional construction.

With the foregoing and other objects in 25 view which will be made manifest in the following detailed description and specifically pointed out in the appended claims, reference is had to the accompanying drawings for an illustrative embodiment of the invention, wherein,

Fig. 1 is a vertical section through the improved gas anchor and sand separator.

Fig. 2 is a horizontal section taken substantially upon the line 2—2 upon Fig. 1.

35 Referring to the accompanying drawings wherein similar reference characters designate similar parts throughout the seat for the standing valve of the pump is indicated at 10 on which the standing valve 11 seats. The gas anchor and sand separator comprises 40 a coupling or collar 12 which adjacent its center has its interior diameter reduced as indicated at 13. The center of the collar is internally threaded as indicated at 14 and both

45 ends of the collar are threaded as indicated at 15 and 16. The upper threaded portion on the collar provides for attachment to the standing valve seat 10. An outer tube or pipe 17 has its upper end threaded into the lower end of the collar 12 so as to be suspended

therefrom. This outer pipe has an aperture 18 formed therein adjacent its upper end constituting an entrance to the gas anchor and sand separator. An intermediate pipe or tube 19 is screwed into the threads 14 on the collar 12 and is suspended thereby within the outer tube or pipe 17. This intermediate pipe or tube is connected to the outer pipe or tube 17 by means of diametrically opposite partitions 20 which may be formed in any suitable manner. The purpose of the partitions 20 is to divide the space within the outer tube or pipe 17 about the intermediate pipe 19 into two semi-cylindrical chambers extending downwardly from the central portion of the collar 12 of the bottom of the intermediate tube 19. These chambers are sealed from each other at the top so that the only passage of communication between the chambers is beneath the bottom of the intermediate tube 19 and the bottoms of the partitions 20. An entrance is made to the interior of the intermediate tube by an aperture 21 which is formed in the intermediate tube adjacent its top and diametrically opposite the entrance 18 so as to be on the other side of the partitions 20 from the entrance. This aperture 21 is also preferably made smaller in size than the aperture 18. The bottom of the intermediate pipe 19 is closed as indicated at 22 and on the bottom of the outer pipe 17 there is fastened a collar 23 which serves to fasten a container 24 having a closed bottom 25 to the bottom of the outer pipe. The gas anchor and sand separator is made complete by an inner pipe or tube 26 which is fastened to the standing valve 11 and suspended thereby within the intermediate tube. This tube 26 may be the tube which is conventionally fastened to the standing valve and suspended thereby.

The operation of the improved gas anchor and sand separator is as follows: The oil in the well enters the device through the aperture 18 and as the gas tends to rise through the oil it will not follow the oil through the aperture 18 but instead will rise about the working barrel. In this manner the gas is effectively separated from the oil at the entrance. The oil which enters the outer tube

17 through the aperture 18 is then caused to pass downwardly until it reaches the bottom of the intermediate tube 19 and the bottoms of the partitions 20. After passing beneath 5 the bottoms of the partitions and the intermediate tube the oil can then rise on the other side of the partitions toward the aperture 21. The turning in the direction of flow of the oil beneath the bottoms of the partitions 10 causes the sand which may be present in the oil to drop out of the oil and settle downwardly into the container 24. Consequently, the oil which rises toward the aperture 21 is relatively free from all particles of sand. 15 When the oil reaches the entrance 21 it enters the intermediate tube and then flows downwardly through the intermediate tube to the bottom of the inner tube 26. At the bottom of the intermediate tube 26 the oil is again 20 caused to reverse its direction of flow so that any particles of sand which might still be with the oil will effectively separate out at this point. It will be found, however, that practically all of the sand will separate from 25 the oil beneath the bottom of the intermediate tube so that very little sand, if any, ever enters the intermediate tube. When the oil enters the inner tube 26 it rises therein and enters the pump to be pumped to the surface. 30 When the pump is pulled for purposes of cleaning or repair the container 24 can be detached from the outer tube or pipe 17 and the sand which has collected therein can be emptied therefrom. From the above described construction it will be appreciated 35 that an improved gas anchor and sand separator is provided which comprises an outer tube and an intermediate tube which are connected to each other by diametrical partitions 40 so that oil entering the outer tube is caused to flow downwardly therein to pass beneath the partitions then upwardly and finally enter the intermediate tube. On entering 45 the intermediate tube the oil is forced to flow downwardly and then upwardly in the inner tube so that there are three reversals in the direction of flow between the entrance to the gas anchor and sand separator and the standing valve. The improved construction 50 is very simple and effectively serves to separate gas and sand from the oil before it enters the pump.

Various changes may be made in the details of construction without departing from 55 the spirit or scope of the invention as defined by the appended claims:

I claim:

1. A gas anchor and sand separator comprising an outer tube adapted to be connected 60 to the bottom of a working barrel, an intermediate tube also adapted to be suspended from the working barrel within the outer tube and an inner tube adapted to be suspended from a standing valve within the intermediate tube, said intermediate tube and outer

tube having closed bottoms, there being an entrance to the outer tube adjacent its top and an entrance to the intermediate tube adjacent its top arranged on the opposite side of the intermediate tube from the entrance 70 to the outer tube, the entrance to the inner tube being adjacent its bottom, and means forming a partition connecting the intermediate and outer tubes from near the top of the intermediate tube to near its bottom. 75

2. A gas anchor and sand separator comprising two tubes arranged one within the other, means for connecting the tubes to a working barrel, means forming a partition connecting the tubes from near the top of the inner tube to near its bottom, there being an entrance to one tube on one side of the partition and an entrance to the other tube arranged on the other side of the partition. 80

3. A gas anchor and sand separator comprising two tubes arranged one within the other, means for connecting the tubes to a working barrel, means forming a partition connecting the tubes from near the top of the inner tube to near its bottom, there being an entrance to one tube on one side of the partition and an entrance to the other tube arranged on the other side of the partition, the entrances being located adjacent the tops 90 of their respective tubes. 95

4. A gas anchor and sand separator comprising an outer tube adapted to be suspended by a working barrel, an intermediate tube adapted to be suspended within the outer tube, and an inner tube adapted to be suspended within the intermediate tube, said intermediate tube having a closed bottom, means providing a partition connecting the intermediate and outer tubes from near the top of the intermediate tube to near its bottom and dividing the space between the intermediate and outer tubes into chambers which can communicate with each other adjacent the bottom of the intermediate tube, there being entrances to the intermediate and outer tubes arranged on opposite sides of said partition, the entrance to the inner tube being adjacent the bottom thereof. 100 105 110

5. A gas anchor and sand separator comprising an outer tube adapted to be suspended from a working barrel, an intermediate tube adapted to be suspended within the outer tube, an inner tube adapted to be suspended within the intermediate tube, the intermediate tube having a closed bottom, means providing a partition connecting the intermediate tube with the outer tube from adjacent its top to a point adjacent its bottom, there being entrances in the intermediate and outer tubes on opposite sides of said partition, the entrance to the inner tube being adjacent its bottom. 115 120 125

In testimony whereof I have signed my name to this specification.

W. J. DUNLAP.
